UNITED STATES PATENT OFFICE.

JAMES MEARS VAN SLYKE, OF MADISON, WISCONSIN.

DESIGN FOR A SPOON.

SPECIFICATION forming part of Design No. 21,717, dated July 19, 1892.

Application filed April 2, 1892. Serial No. 427,546. Term of patent 7 years.

To all whom it may concern:

Be it known that I, JAMES MEARS VAN SLYKE, residing at Madison, in the county of Dane and State of Wisconsin, have invented 5 and produced a new and original Design for Spoons, of which the following is a specification.

Reference is to be had to the accompanying drawing, forming a part of this specification, 10 in which the figure represents a face view of a spoon having my new design embodied in the handle thereof.

The design embraces features commemorative of the eagle "Old Abe," which accompanied 15 a Wisconsin regiment through the war of the rebellion.

The design consists in the ornamentation of the handle of a spoon, the essential feature of which is the figure of an eagle.

20 The letter *a* indicates the figure of the eagle, the same being the termination or a continuation of the handle, and represented

as perched on a transversely-disposed block *b*, the latter appearing as if supported on the end of the handle, which is in the form of a 25 trunk of a tree *c*. A chain *d* is represented as securing the eagle to the tree *c*. On one side of the handle, near the top, appears below the block *b* a second trunk or growth *c'*. At the base of the handle appears a foliate 30 scroll *e*.

In the merchantable article any suitable explanatory inscription may appear on the spoon—such, for instance, as the figures "1861-'65" and the words "Old Abe" and 35 "Wisconsin."

I claim—

The design for a spoon herein shown and described.

JAMES MEARS VAN SLYKE.
